UNITED STATES PATENT OFFICE.

MARCELLO VON PIRANI, OF WILMERSDORF, GERMANY, ASSIGNOR TO GENERAL ELECTRIC COMPANY, A CORPORATION OF NEW YORK.

INCANDESCENT LAMP.

1,099,721.

Specification of Letters Patent.

Patented June 9, 1914.

No Drawing.

Application filed November 23, 1912. Serial No. 733,075.

To all whom it may concern:

Be it known that I, MARCELLO VON PIRANI, a citizen of the Italian Kingdom, residing at Wilmersdorf, near Berlin, Germany, have 5 invented certain new and useful Improvements in Incandescent Lamps, of which the following is a specification.

The object of my invention is to prolong the life and increase the efficiency of tungsten or other metallic filament lamps. For 10 this purpose it has heretofore been proposed to operate the filament in a halogenous atmosphere. In practice, however, it is a more or less difficult task to liberate the halogen 15 gas or vapor in just the proper amount for the best operation of the lamp. I have discovered that when certain metallic halogen compounds are subjected to the action of the light and heat action of the filament they 20 are decomposed and the halogen liberated in the bulb. I have found that chlorid of silver is a suitable compound for this purpose.

Beneficial results may be obtained by the 25 use of the halogen compound alone or in combination with a chemically active metal used as a carrier for the compound. Chlorid of silver, for example, is placed in the bulb in such manner that it is acted on by 30 the light and heat action of the filament and may be located at any suitable distance from the filament. Its location determines the rapidity with which the gas is liberated and this may be determined by trial for each 35 size or class of lamps. Further the compound may be mounted on a carrier of suitable metal and of suitable design. For best results I have found that carriers of nickel, iron or similar metals are particularly satisfactory for this purpose, and a satisfactory arrangement of the carrier is in the form of a small gauze or network. I have found also that a particularly good combination for tungsten filament lamps is the use of 40 chlorid of silver on a carrier of nickel. The compound may be melted onto the carrier and the carrier with the compound thereon

is then mounted in the lamp in a suitable location with respect to the filament. The carrier may be mounted on the central filament supporting stem. In some cases it may be folded about said stem. It may be that the carrier which is in intimate contact with the compound and is therefore subjected to substantially the same conditions 55 as the compound regulates the amount of gas or vapor liberated whereby more uniform liberation and consequently better results are obtained than if an indifferent carrier were used, or it may be that the carrier 60 has some other chemical relation to, or effect on, the behavior of the compound or the gas or vapor liberated therefrom. It is to be understood, however, that good results may be obtained by the use of a halogen 65 compound of silver mounted on a chemically indifferent carrier.

What I claim as new and desire to secure by Letters Patent of the United States, is:—

1. An incandescent lamp comprising a 70 bulb, a tungsten filament mounted therein, and a halogen compound of silver in said bulb in effective relation to said filament.
2. An incandescent lamp comprising a 75 bulb, a tungsten filament mounted therein, a halogen compound of silver in said bulb in proximity to said filament, and a carrier for said compound.
3. An incandescent lamp comprising a 80 bulb, a tungsten filament mounted therein, chlorid of silver in said bulb in proximity to said filament, and a metallic carrier for said chlorid.
4. An incandescent lamp comprising a 85 bulb, a tungsten filament mounted therein, chlorid of silver in said bulb, in operative relation to said filament, and a carrier of nickel for said chlorid.

In witness whereof, I have hereunto set my hand this fifth day of November, 1912. 90
MARCELLO VON PIRANI.

Witnesses:

HENRY HASPER,
WOLDEMAR HAUPT.
